United States Patent Office

Des. 181,008
Patented Sept. 17, 1957

181,008

LOW LEVEL FROZEN FOOD MERCHANTISER

Frederick J. Kuhn, Detroit, Mich.

Application February 9, 1956, Serial No. 40,096

Term of patent 14 years

(Cl. D80—11)

Fig. 1

Fig. 2

Fig. 1 is a perspective view of a low level frozen food merchandiser, showing my new design; and

Fig. 2 is an end elevational view taken from the side opposite that shown in Figure 1.

The rear or portion opposite that shown in Fig. 1 is substantially the same as the front shown.

I claim:

The ornamental design for a low level frozen food merchandiser, substantially as shown and described.
